CASE FOR ELECTROPHONIC INSTRUMENTS

Chester T. Weir, Buffalo, N. Y.

Application November 9, 1938, Serial No. 239,681

3 Claims. (Cl. 206—13)

This invention relates to electrophonic stringed instruments.

It is an object of the invention to simplify the task of the musician who is called upon to give a number of recitals during the day's work, by providing a portable case which may house built-in amplifying and speaker units, as well as the instrument itself.

A further object of the invention is to so fashion the instrument case that it may be used as an easel for sheet music, so that the instrumentalist may have readily available the music, the electrical controls of the device, and the necessary accessories for aiding in playing the instrument.

The invention will also be found to reside in the location of the loud speaker in a position where best acoustic effects may be obtained, and in other structural features which are more specifically described in the accompanying specification and drawing, wherein:

Fig. 1 is a side elevation of the case in closed position;

Fig. 2 is a perspective view of the case in open position;

Fig. 3 is a vertical section through the case, as viewed in Fig. 2;

Fig. 4 is a perspective view of the small cover section showing the ledge attachment; and

Fig. 5 is a perspective view of the volume control attachment.

The case 10 includes a rectilinear body 11 having an open side 12 which is closed by a pair of hinged cover sections 13 and 14. The larger of the cover sections 13 is connected by hinges 15 to one of the long sides 16 of the body, and thus it is adapted to open laterally. The cover section 14 is connected by hinges 17 to the end wall of the body. The section 13 carries a protective weather strip 18, which covers the adjacent margins of the section 14 when in closed position. Clasps 20, of the usual type, are provided to fasten the sections to the body, and the body is provided with a centrally located carrying handle 21.

A rest 22 is mounted on a support 23 at one end of the body compartment, while a bracket 24 containing an angular notch 25 is secured to the corner of the opposite end of the body. These members serve as a support for a guitar 27, or other stringed instrument, the sound box or head 27a thereof being positioned in a form fitting pocket 22a in the rest 22, and the tongue board 27b being received in the notch 25 of the bracket 24.

An amplifying unit 30 is secured within the

body to the side 16 in a position where it clears the supported guitar. The bottom wall 31 of the body contains a circular aperture 32 located opposite the cover section 14, and it is covered by a speaker unit 33.

As will be seen in Fig. 1, the case 10 containing the guitar and electrical units, is in convenient form to be carried from place to place, as its bulk, due to the compact arrangement of the enclosed elements, is but little larger than the usual instrument case.

On location, the guitar is removed, and the case is positioned on its end 33, as shown in Fig. 2, with the large hinged cover section 13 swung open to provide a support. The section 14 is likewise swung open to a fixed position limited by a hinged brace 34, and thus it forms an inclined easel for the reception of sheet music. The instrumentalist is seated behind the open case, where the controls of the electrical elements are conveniently available. In addition, the cover section 13 is supplied with a pocket 35, wherein may be stored the sheet music, which is available for selection and positioning on the easel section 14.

The section 14 at its lower edge 14a carries a pair of studs 38 for receiving the slotted portions 39 of a ledge member 40. When the case is opened, the member 40 is raised to the position shown in dotted lines in Fig. 4, where it serves as a support for the sheet music. The member 40 is formed with a tail piece 41, which, when in retracted position, abuts the end of a leaf spring 42 secured to the interior of the section 14. The spring is formed with a curved seat portion 43 which engages the tail piece when the ledge member is moved to its operative position, and thus retains it against accidental displacement. It will be observed that the adjoining ends or walls 13a, 14a of the cover sections and the body of the ledge member 40 are notched to clear the neck 27c of the guitar when the case is closed.

In the operation of the loud speaker unit, it will be observed that the case positions it in an elevated position, which is desirable for proper acoustic effects. The operation of electrophonic stringed instruments is so well known in the art that it is not deemed necessary to show specific circuits, and the like. In the present device, the amplifying unit 30 is connected to a power source S through a cord 50, while the electrical portion 50 of the guitar is connected to the unit 30 by a cord 51, as shown in Fig. 3.

When playing the instrument, it is advantageous to free the hands of the labor of adjusting the volume control of the unit 30. This is 55

accomplished by providing a spring-pressed lever 55, which is pivoted as indicated by the numeral 56 to the rest 22 (Fig. 3). The projecting arm 57 of the lever carries a rod 58 which extends upward for connection with an arm 60, which is secured to the pintle 61 of the tone control instrumentality of the unit 39. As best shown in Fig. 5, it will be observed that a pedal 62 is pivotally mounted on the arm 57 of the lever 55, and it is formed with a lug 63 which engages the lower side of the arm 57, and thus unites the pedal and lever for unitary downward movement. When it is desired to close the case, the projecting pedal 62 is swung upward to an unobtrusive position.

It will be apparent to those skilled in the art that the arrangement of elements and the general design of the case may be varied in accordance with the shape of the instrument and the character of the electrical units without departing from the inventive concept, as set forth in the following claims.

I claim:

1. An elongated rectilinear instrument case having a bottom and an opposed open side, said bottom being formed with an aperture adjacent one end thereof, electrically connected amplifying and speaker units mounted within the case with the speaker unit disposed over the aperture of the case bottom, said amplifying unit including an adjustable control instrumentality, means for removably supporting an electrophonic stringed instrument within the casing, a flexible electrical connection between the instrument and the amplifying unit, a laterally hinged closure for the open side of the case, said closure when open being adapted to serve as a support when the case is positioned on an end opposite said speaker unit, control operating means comprising a pedal supported within said last named end of the casing and having an extensible section movable to a position exterior of the casing when the closure is opened, and a mechanical linkage between said pedal and said control instrumentality of the amplifying unit.

2. An elongated rectilinear instrument case having a bottom and an opposed open side, said bottom being formed with an aperture located adjacent one end thereof, electrically connected amplifying and speaker units mounted within the case with the speaker unit disposed over the aperture of the case, a supporting structure within the opposite extremity of the case for removably receiving the head of an electrophonic stringed instrument, other supports in the casing located adjacent said units for receiving the tongue board of the instrument, a flexible electrical connection between the instrument and the amplifying unit, and a laterally hinged closure for the open side of the case, said case being adapted to be stood on said last named end with said closure in open position serving as a supporting element.

3. An elongated rectilinear instrument case having a bottom and an opposed open side, said bottom being formed with an aperture located adjacent one end thereof, electrically connected amplifying and speaker units mounted within the case with the speaker unit disposed over the aperture of the case, a supporting structure within the opposite extremity of the case for removably receiving the head of an electrophonic stringed instrument, other supports in the case located adjacent said units for receiving the tongue board of the instrument, a flexible electrical connection between the instrument and amplifying unit, a pair of cover members cooperating to close the open side of the case, one cover member being hinged at said first end of the case, the free extremity of said first cover member having a marginal projecting member secured thereto to provide a support for sheet music, braces in the case for supporting the first cover member in an angular open position to provide a music easel when the case is supported on its remaining end, the second cover member being hinged to the case for lateral opening movement whereby when in open position it serves as a supporting structure for the case.

CHESTER T. WEIR.
